TABLE KNIFE

Gert Holbek, Lyngby, Copenhagen, and Jørgen Dahlerup,
Copenhagen, Denmark, assignors to Georg Jensens
Solvsmøde A/S, Copenhagen, Denmark

Filed Aug. 24, 1962, Ser. No. 71,447

Claims priority, application Denmark Feb. 26, 1962

Term of patent 14 years

(Cl. D22—3)

Fig. 1

Fig. 2

Fig. 3

Fig. 4

FIGURE 1 is a top plan view of a table knife illustrating our design,

FIGURE 2 is a side elevational view thereof,

FIGURE 3 is another side elevational view showing the side opposite to that of FIGURE 2, and

FIGURE 4 is a sectional view taken substantially along the line IV—IV of FIGURE 1.

We claim:

The ornamental design for a table knife, as shown.
